GARMENT COVER AND THE METHOD OF
CONSTRUCTING THE SAME

Morris Katz, Bronx, N. Y.

Application February 16, 1938, Serial No. 190,711

5 Claims. (Cl. 223—98)

This invention relates to devices for use upon garments and other articles of apparel when suspended from a hanger for protecting the top, shoulder and neck portions of the garment or other article of apparel, especially in the storage and display thereof, and the object of the invention is to provide a cover of the class described formed from a substantially rectangular sheet of paper or other thin material, folded and secured together to form front and rear portions joined at the upper edge with an opening for receiving a garment hanger hook, one side portion of the cover being formed from an uninterrupted portion of the sheet, whereas the other side portion thereof consisting of opposed sides of the sheet are brought together and have overlapping corner portions which are glued or otherwise secured together so as to form downwardly extending and substantially pointed ends to the separate parts forming the last mentioned side portion of the cover, a further object being to provide a cover of the class described, the first named side portion of which includes a protruding ticket or portion joining the cover in a rupturable or perforated line whereby the ticket may be removed whenever desired, a further object being to provide a device of the character described which, by virtue of the method of its construction, is formed from an elongated strip of material which is so cut as to form a successive series of covers from the material of the strip without any waste of such material, and still further to a method of creasing, folding and securing the parts of the blank together in forming the cover as more fully hereinafter described and claimed.

The invention is fully disclosed in the following specification, of which the accompanying drawing forms a part, in which the separate parts of my improvement are designated by suitable reference characters in each of the views, and in which:

Fig. 1 is a front view of one form of my device made according to my invention and diagrammatically illustrating the method of its use.

Fig. 2 is a plan view of a blank from which the device shown in Fig. 1 is formed.

Fig. 3 is a partial section on the line 3—3 of Fig. 1.

Fig. 4 is a view similar to Fig. 1 showing another form of construction, and

Fig. 5 is a plan view of a blank from which the device shown in Fig. 4 is formed.

In the storage and display of garments and other articles of apparel it is customary to arrange the same upon hangers supported on a

rack or other mounting in display cabinets, in closets, on racks, and in like places, both in the commercial display of merchandise of this kind as well as in the storage of apparel in closets or wardrobes in the home. The purpose of my invention is to provide a covering or shield for the upper shoulder and neck portions of garments or apparel, supported or suspended in this manner, to eliminate the collection of dust thereon. In view of the extensive possible use for devices of this kind, it is desirable to produce the same as economically as possible in order that a relatively large number of the devices may be sold at a reasonable price, not only for the commercial use of the display, but also for the home use thereof.

To accomplish the results above claimed, I have conceived a method of so cutting each sheet, from which the complete device is formed, from an elongated strip of paper or other material, so as to eliminate all waste, and to effectively utilize every portion of the sheet in the resulting blank to produce the desired function in the resulting article.

In Fig. 2 of the drawing I have indicated at 10 in dotted lines, a strip or sheet of suitable paper. At 11 I have shown one of the successive series of blanks which are cut from the strip 10. One edge 12 of the blank has a central rectangular notch 13 extending approximately one-third the way across the main body portion of the blank. The notch or recess portion 13 forms on the other edge 14 of a previous blank, a ticket or tab 15 joining the edge 14 in a rupturable or perforated line 16 whereby the ticket 15 may be removed whenever desired. This ticket may have printed or otherwise applied thereto any indicia which may be desired.

The sides of the blank at the ends of the edge 12 terminate in projecting pointed flags 17 which serve to protect a greater portion of the garment as will appear from a consideration of Fig. 1 of the drawing. The size of these flaps may be varied to suit different uses for which the resulting device or devices are intended. The formation of the flaps 17 upon the edge 12 of the blank will result in angular or beveled corners 18 at the ends of the edge 14. These beveled corners will produce a neater appearance and will substantially parallel other edges of the complete device as seen in Fig. 1. In addition to producing a neater appearance these beveled corners will obviate folding or wrinkling of the cover when placing two garments side by side, especially upon a crowded or congested rack.

- In forming the blank 11 two creases 19 and 20 are formed therein extending from the edge 14 to the side edges of the blank in the angular arrangement shown in Fig. 1, so that in the successive steps of the method in forming the complete device, side portions 21 and 22 may be folded inwardly upon a part 23 in the manner shown in Fig. 1, with a corner portion 24 arranged over a corner portion 25. Prior to this operation a section of glue or other adhesive 26 is applied to one of the corner portions 24, 25, the corner portion 24 in the construction shown, so that said overlapped corner portions will be secured together in the manner indicated in Fig. 1.
- 15 In fact, the application of the glue 26 may be applied to the sheet prior to die cutting the same. In this connection it will be understood that the cover devices are produced automatically in a successive series of operations in a suitable machine into which the strip 10 is fed. The glue is applied, the blanks 11 cut and then folded and creased along the lines 19 and 20 producing the result shown in Fig. 1. After this, the resulting devices may be bundled or packed for shipment 25 and in some cases the same may be folded upon itself a number of times to form smaller packages. The latter would be especially desirable in retailing a half-dozen or dozen of the devices for domestic use.
- 30 It will be understood that in folding and securing the parts 21 and 22 together, an opening 27 is formed at the top of the device through which a hook 28 of a garment hanger 29 may be passed in the manner illustrated in Fig. 1. 35 In said figure I have indicated in dotted lines at 30 the upper portion of a garment arranged upon the hanger and supported within the cover or shield.
- It will be understood that the device may be 40 arranged in any manner upon the garment, but for the sake of description, the part 23 will be said to cover the back of the garment and the parts 21 and 22 collectively covering the front of the garment.
- 45 In a device of the character described it is primarily important that the shoulders and neck of the garment be protected. However, with my construction the cover or shield extends downwardly at the back as well as at the front of the garment to provide a relatively large shielding area which will, to a great degree, prevent the collection of dust upon any part of the garment.
- 55 In Figs. 4 and 5 of the drawing I have shown a slight modification wherein a blank 11a is formed from a strip 10a and is cut to form a notch or recess 13a and resulting ticket or tab 15a. The blank 11a is scored as seen at 19a and 20a, all substantially as seen in Fig. 2 of the drawing. The adhesive is indicated at 26a. In other words, the only difference between the structure shown in Fig. 5 and that shown in Fig. 2 is in omitting the flaps 17 and the resulting beveled corners 18 on the complete device, thus 65 producing on the finished device the result substantially the same as that illustrated in Fig. 4. An opening 27a is formed in the top of the device similar to the opening 27, and the side portions 21a and 22a will have their corners 24a, 25a overlapped and secured together as in the construction shown in Fig. 1. The type of structure shown in Figs. 4 and 5 would be desirable for use 70 on larger garments, such as overcoats and the like to give greater protection to the shoulder portions of the garment. However, with lighter

materials and smaller garments, the structure shown in Fig. 1 of the drawing is more desirable for the reasons stated.

It will be understood that the device may be made from any kind or class of sheet material, including "Cellophane" and similar transparent materials or semitransparent or translucent materials, as well as from lightweight papers of any kind or class which may be printed or otherwise characterized to give attractive appearance thereto.

Having fully described my invention, what I claim as new and desire to secure by Letters Patent, is:

1. The herein described method of forming 15 garment covers of the class described, which consists in providing an elongated strip of sheet material, successively cutting and scoring said sheet to form a blank having a notch centrally of one edge, a projecting ticket centrally of the opposed edge, and diverging score lines extending from the base of the notch to opposite sides of said blank forming foldable side parts at opposite sides of the notch in said blank, then folding the blank on said score lines to bring said side 25 parts one upon the other and upon the body of the blank with adjacent corner portions of said parts arranged in overlapped relation to each other, securing said overlapped corner portions together to form the resulting garment cover, 30 then forming another garment cover blank from the next section of the sheet, and forming the notch of the second blank by the ticketed portion of the preceding blank to eliminate any waste of material in the production of a successive 35 series of devices.

2. The herein described method of forming garment covers of the class described, which consists in providing an elongated strip of sheet material, successively cutting and scoring said sheet 40 to form a blank having a notch centrally of one edge, a projecting ticket centrally of the opposed edge, and diverging score lines extending from the base of the notch to opposite sides of said blank, forming foldable side parts at opposite 45 sides of the notch in said blank, then folding the blank on said score lines to bring said side parts one upon the other and upon the body of the blank with adjacent corner portions of said parts arranged in overlapped relation to each other, securing said overlapped corner portions together 50 to form the resulting garment cover, then forming another garment cover blank from the next section of the sheet, forming the notch of the second blank by the ticketed portion of the preceding blank to eliminate any waste of material 55 in the production of a successive series of devices, and so cutting each blank as to form projecting flaps at the first named edge thereof and correspondingly beveled corners at the other 60 edge thereof.

3. The herein described method of forming garment covers of the class described which consists in automatically cutting and scoring a successive series of blanks from an elongated strip 65 of sheet material without producing any waste of the material of said sheet, then shaping each blank so as to produce front and rear portions of a garment cover joined in diverging upper edges terminating centrally in an opening, forming the front portion of the cover from separate side parts of the blank, and overlapping and securing portions of said parts together in forming said cover.

4. A garment cover of the class described 75

- formed from a single substantially rectangular sheet of material, the side edges of said sheet being parallel, and the upper and lower edges being parallel through the greater portion of their length and perpendicular to said side edges, the lower edge of said sheet having a projecting portion centrally thereof and the upper edge of said sheet having a correspondingly shaped notched portion, said sheet being scored in diverging lines from said notch to corresponding points approximately centrally of said side edges to form parts foldable upon the remainder of the sheet, said parts overlapping at corner portions thereof, said corner portions being secured together forming of the complete device a cover having a central opening at the top thereof, and the projecting portion of said sheet forming a ticket joining the sheet in a perforated line permitting removal thereof.
5. A garment cover of the class described formed from a substantially rectangular sheet of material, one edge portion of the sheet having a predetermined irregular contour including a
- projecting portion centrally of said edge, and the opposed edge of said sheet having a similarly irregular contour including a notched portion centrally thereof, the side edges of said sheet intermediate said irregular opposed edges being parallel, and said sheet being scored in diverging lines from said notch to corresponding points approximately centrally of said side edges, the portion of said sheet between said score lines forming the back wall of said cover, the other portions of said sheet outwardly of said score lines being arranged over said back wall with adjacent corners of said portions overlapped and secured together to form a front wall for the cover, said front wall having an opening centrally of the upper edge thereof, and the other free corners of said portions outwardly of said score lines extending slightly below the lower edge of said rear wall at points intermediate the side edges and projecting central portion of said rear wall.
